(57) **CLAIM**

The ornamental design for a dust cover for small kitchen appliances, as shown and described.

DESCRIPTION

FIG. 1 is a front perspective view of a dust cover for small kitchen appliances showing my ornamental design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged portion view thereof as shown in FIG. 1.

The dash-dash broken lines illustrate portions of the dust cover for small kitchen appliances that form no part of the claimed design. The dash-dot-dash lines encircling the enlarged views are for annotative purposes only and form no part of the claimed design.
